TOBACCO PIPE

Kenly C. Bugg, 1202 Sunset Drive,
Fort Wayne, Ind. 46807
Filed Apr. 16, 1965, Ser. No. 448,757
9 Claims. (Cl. 131—201)

ABSTRACT OF THE DISCLOSURE

A tobacco pipe construction which is simple and inexpensive, but which produces very desirable smoking and handling properties. The tobacco pipe generally comprises a tobacco-receiving bowl and a pipe stem through which the smoke from the bowl may be drawn. A bit is joined to one end of the stem, and the other end of the stem is adapted to be received within a transverse bore in the base of the bowl. This other end of the stem is positioned in the transverse bore in a manner which defines a chamber external of the stem for receiving smoke drawn from the tobacco-receiving bowl and for collecting the moisture and other condensates from the smoke, while permitting the smoke to freely flow from the pipe bowl through the stem.

Brief summary of the invention

This invention relates to a tobacco pipe.

Among the objects of this invention are:

- (a) To provide a pipe of relatively simple construction, having very desirable smoking properties, an attractive appearance, and a suitable weight and feel.
- (b) to provide a pipe which has a simplified bowl construction without an integrally formed stem portion, but which is capable of being readily assembled with a removable stem so that a firm and positive engagement is provided between the two components.
- (c) To provide a tobacco pipe having a construction such that even combustion of much of the entire load of tobacco is insured.
- (d) To provide a tobacco pipe in which the bowl and stem, when assembled, form a novel passageway for the smoke that insures against clogging and the undesirable entry of moisture into the stem.
- (e) To provide a bowl and stem construction which will insure against the freezing of these two components in assembled relation, but which will provide a seal therebetween which insures against the leakage of fluids into areas where their presence is undesirable.
- (f) to provide a tobacco pipe which has components that are not only readily disassembled, but lend themselves to being readily disassembled, but lend themselves to being readily cleaned with a minimum of effort.
- (g) To provide a tobacco pipe comprising three basic components of simple design and construction which are very readily and economically manufactured.

Description of a preferred embodiment

Other objects and advantages of this invention will become evident as the description proceeds and from an examination of the accompanying drawing which illustrates an embodiment of the invention and in which similar numerals refer to similar parts throughout the several views.

In the drawing:

FIGURE 1 is a plan view from above of a tobacco pipe, embodying one form of the invention.

FIGURE 2 is a view principally in vertical cross-section, with certain portions broken away and others shown in side elevation, of the pipe shown in FIGURE 1.

FIGURE 3 is an end view in vertical cross-section of

2

the pipe shown in FIGURE 2, the view being taken along the line 3—3 in that figure.

FIGURE 4 is an enlarged view in vertical cross-section of the stem portion of the pipe shown in FIGURE 5 1, illustrating some of the constructional features in more detail.

Referring now to FIGURES 1 and 2, the tobacco pipe shown therein is made up of three basic components: the bowl 10, the stem 12, and the bit 14. As best shown in FIGURE 2, one end 16 of the stem 12 is adapted to be received in the transverse bore 18 in the base 19 of the bowl 10. The upper portion of the bore 18, as best shown in FIGURE 1, communicates with the base of the longitudinal bore 20 in the bowl 10 through the elongated opening 22 in the tapered bottom 23 of the bore 20, the latter being adapted to be filled with tobacco when the pipe is in use.

The stem 12 is preferably formed of a suitable metal such as aluminum, and is preferably in the form of seam-20 less tubing circular in cross-section. The stem may have other suitable cross-sectional configuration intermediate its two ends, however, if such is desired for ornamental or functional purposes. The end 24 of the stem 12 is adapted to receive the end 26 of the bit 14 in tight-fitting 25 relation. Preferably, this joint is a permanent one so that the flattened end 28 of the bit 14 is fixed so that it is always disposed in a plane parallel to the plane of the two diametrically opposed slots 30 and 32 in the opposite end 16 of the stem 12, which slots are best shown 30 in FIGURES 3 and 4.

Immediately adjacent the end 16 of the stem 12 the outer diameter of the stem 12 is slightly reduced, along a short length of the stem 12, providing an area of reduced diameter 34 which has a length somewhat greater 35 than the length of the opening 22 in the bottom of the tobacco receiving bore 20 in the bowl 10. A step or collar 36 is thus formed at the end 16 of the stem 12, which collar may have a bevelled edge 38 adapted to be received in alignment with the conical end 40 in the side 40 wall of the bowl 10 of the transverse bore 18.

As best shown in FIGURE 3, the area of reduced 45 diameter 34 of the stem 12, in conjunction with the bore 18, forms a tubular passageway 42 circumscribing the stem 12 which passageway communicates with the opening 22 and likewise with the slots 30 and 32 in the stem 12. This passageway thus forms a path for the smoke from the interior of the tobacco receiving bore 20 in the bowl 10 to the interior of the stem 12, the smoke being drawn from the bore 20 through the opening 22 into the passageway 42 and downwardly around the area of reduced diameter 34, through the slots 30 and 32, into the interior of the stem 12 and thence down the stem and out the bit 14.

The portion of the tubular passageway 42 which is 50 below the slots 30 and 32 will function as a reservoir for moisture which may be condensed from the smoke within the passageway 42. This reservoir has the advantage of being removed from the path of the smoke and so disposed that moisture condensing within the passageway 42 will flow by gravity downwardly into the reservoir area rather than into the interior of the stem 12. The retention of the moisture in the reservoir is insured by the fact that a tight seal is established at the two ends of the bore 18 between the sides of the bore and the outer surface of the stem 12, at the right end of the bore 18, as viewed in FIGURE 2, and below the slots 30 and 32 at the left end of the bore 18, as viewed in the same figure. The lower half of the collar 36 at the end 16 of the stem provides this seal at the left end of the bore 18, while the area of normal diameter of the stem, within 55 70 the right end of the bore 18 forms the seal at that end.

The slotted construction of the stem 12 adjacent its end 16 in addition to providing communication with the interior of the stem, is particularly important in connection with the proper interfitting relation between the bowl 10 and the stem 12 and the formation of the seals just discussed. When the stem 12 is being inserted in the bore 18, the slots 30 and 32 permit the collar 36 on the inner end of the stem to flex slightly, in accordance with variations in the diameter of the longitudinal axis of the bore 18. This feature insures against binding of the stem 12 within the bore 18, but nevertheless permits the tolerances to be small enough to insure that a very tight seal is maintained at the two ends of the bore 18, as described in the preceding paragraph. Not only does this permit this type of close-fitting construction to be provided initially in a new pipe, but it also insures against later difficulty after the pipe has been in use in the event that some distortion of the bore 18 has occurred due to the high heat and moisture content which are always found within a pipe bowl when in use.

A further feature is incorporated in the stem 12 which insures against the very undesirable freezing or sticking of the stem 12 in the bore 18 because of a build-up of deposits, particularly at the extremities of the opening 22. As best shown in FIGURE 2, the area of reduced diameter 34 extends slightly beyond the outer extremities of the opening 22 and leaves exposed a portion of the shoulders 44 and 46 formed at the junction of the bores 18 and 20. This construction makes it readily possible to shear any deposits which may be formed between the sides of the bore 20 and the stem 12, by a simple withdrawal of the stem 12 combined with a twisting motion thereof, relative to the bowl 10 since any deposits building up between the sides of the bore 20 and the portion 34 of the stem 12 will form a bridge between the overhanging shoulders 44 and 46 and the portion 34 adjacent thereto.

A further novel and desirable feature of the invention is that the area of reduced diameter 34 on the stem 12 is provided with a slight taper in the direction of the end 16 of the stem 12. The area 34 thus has the configuration of a truncated cone. The result of such a construction is that the passageway 42 for the smoke has an increasing volume as one moves from the undercut area 46 toward the undercut area 44. This variation in the volume of the passageway 42 is provided so that an even combustion of much of the entire load of tobacco is insured as well as the elimination of the "hot spot" normally found in a conventional pipe. The path of the burning of the tobacco will normally follow the line of the shortest draw. In other words, if the passageway 42 had the same volume throughout its length, the area of combustion would project downwardly into the bowl toward the end of the opening 22 which is adjacent the undercut area 46. By opening up the opposite end of the passageway 42, a greater volume of air is drawn at the end of the passageway 42, which is adjacent the undercut portion 44 than is drawn at the opposite end adjacent the undercut area 46. This differential in volume compensates for the shorter path of the draw to the end of the opening 22 adjacent the undercut portion 46, and the end result is that an even combustion of the entire load of tobacco is produced. The path of burning, therefore, moves downwardly in a symmetrical fashion toward the opening 22, as the pipe is smoked.

It has been found to be preferable to shape the bowl portion 10 of the pipe in such a way that the transverse dimension of the base 19 of the bowl is longer along the axis of the bore 18 than it is in a direction normal thereto. In other words, the width of the bowl at the base 19 is substantially greater in the cross-section shown in FIGURE 2 than it is in the cross-section shown in FIGURE 3. The purpose of this configuration is to provide a greater mass of material along the axis of the bore 18 so that adequate bearing surfaces may be pro-

vided between the bowl 10 and the stem 12 without weakening the side walls of the bowl 10 to an undesirable degree. As shown in FIGURE 1, a bowl of generally octagonal shape on its outer surface is particularly suitable for this purpose.

It may thus be seen that the invention provides a tobacco pipe of simple, inexpensive construction which, nevertheless, has very desirable smoking and handling properties, as well as an attractive appearance.

In the drawing and specification there has been set forth a preferred embodiment of the invention, and although specific terms are employed, they are used in a generic and descriptive sense only and not for purposes of limitation. Changes in form and in the proportion of parts, as well as the substitution of equivalents, are contemplated, as circumstances may suggest or render expedient, without departing from the spirit or scope of this invention, as further defined in the following claims.

What is claimed is:

- 20 1. A pipe for smoking tobacco comprising: a bowl having a longitudinal tobacco-receiving bore defined by a bowl wall and a lower bowl base; a transverse bore in said bowl base having an open end at said bowl wall for receiving a pipe stem and communicating intermediate its ends with the lower end of said longitudinal bore; a tubular stem having one end adapted to be received within said transverse bore and having a bit member joined to the other end thereof, said one end of said stem having axially spaced portions adapted to frictionally engage the extremities of said transverse bore and establish a seal between said transverse bore and said stem; a length of said stem between said spaced portions having a reduced diameter in relation to the diameter of said transverse bore to provide a chamber in said transverse bore external of said stem for receiving smoke drawn from tobacco burning in said longitudinal bore; and means providing slots in said one end of said stem substantially coincident with said length of reduced diameter to bring said chamber in communication with the interior of said stem, said slots being disposed on said stem to permit condensates of smoke drawn from said chamber into said interior of said stem to be collected within said chamber in said transverse bore.
- 25 2. A pipe for smoking tobacco of the character defined in claim 1, further characterized in that said length of reduced diameter of said stem is in the shape of a truncated cone with the base of said cone being nearest said open end of said transverse bore so that the volume of said chamber varies gradually along said length of said reduced diameter of said stem to a minimum volume nearest said open end of said bore.
- 30 3. A pipe for smoking tobacco of the character defined in claim 1, further characterized in that said length of reduced diameter terminates short of the extremity of said one end of said stem, and wherein a collar of enlarged diameter is provided adjacent said extremity of said stem for frictionally engaging said transverse bore.
- 35 4. A pipe for smoking tobacco of the character defined in claim 1, further characterized in that said slots of said stem open into the extremity of said one end of said stem so that the diameter of said one end can adjust to variations in the diameter of said transverse bore.
- 40 5. A pipe for smoking tobacco of the character defined in claim 1, further characterized in that said transverse bore communicates with said longitudinal bore through an elongated opening having a width substantially less than the diameter of said transverse bore.
- 45 6. A pipe for smoking tobacco of the character defined in claim 5, further characterized in that the length of reduced diameter on said stem has a length greater than the length of said elongated opening.
- 50 7. A pipe for smoking tobacco of the character defined in claim 1, further characterized in that said slots in said stem are disposed in a plane substantially parallel to the plane of said bit member.
- 55 8. A pipe for smoking tobacco of the character defined in claim 1, further characterized in that the transverse bore has a transverse dimension which is greater than the longitudinal dimension of the bowl.
- 60 9. A pipe for smoking tobacco of the character defined in claim 1, further characterized in that the transverse bore has a transverse dimension which is less than the longitudinal dimension of the bowl.
- 65 10. A pipe for smoking tobacco of the character defined in claim 1, further characterized in that the transverse bore has a transverse dimension which is substantially equal to the longitudinal dimension of the bowl.
- 70 11. A pipe for smoking tobacco of the character defined in claim 1, further characterized in that the transverse bore has a transverse dimension which is greater than the longitudinal dimension of the bowl.
- 75 12. A pipe for smoking tobacco of the character defined in claim 1, further characterized in that the transverse bore has a transverse dimension which is less than the longitudinal dimension of the bowl.

8. A pipe for smoking tobacco of the character defined in claim 1, further characterized in that said bowl base is of greater thickness in a direction axial to said transverse bore than the thickness of said base in a direction normal to said transverse bore.

9. A pipe for smoking tobacco comprising: a bowl having a longitudinal tobacco-receiving bore defined by a bowl wall and a lower bowl base; a transverse bore in said bowl base communicating intermediate its ends with said longitudinal bore through an elongated opening having a width substantially less than the diameter of said transverse bore and having an open end at said bowl wall; a stem having one end adapted to be received within said transverse bore in tight fitting relation with the extremities of said bore and having a length therebetween of a reduced diameter in relation to the diameter of the transverse bore, said length of reduced diameter being greater than the length of said elongated opening, and having the shape of a truncated cone so that the base of said cone is nearest said open end of said transverse bore, so that said transverse bore defines a chamber surrounding said length of reduced diameter of said stem for receiving smoke from said longitudinal bore with the volume of said chamber varying gradiently along the length of said stem to a minimum volume nearest said

open end of said transverse bore; slots in said end of said stem disposed substantially coincident with said length of reduced diameter but opening into the extremity of said one end of said stem so that the diameter of said one end can adjust to variations in the diameter of said transverse bore; and a bit member disposed in tight fitting engagement with the other end of said stem so that the plane thereof is substantially parallel to the plane of said slots.
